UNITED STATES PATENT OFFICE.

FRIEDRICH PHILIPP, OF NEW YORK, N. Y.

PUNCHING-MACHINE.

SPECIFICATION forming part of Letters Patent No. 557,018, dated March 24, 1896.

Application filed October 4, 1895. Serial No. 564,646. (No model.)

To all whom it may concern:

Be it known that I, FRIEDRICH PHILIPP, a citizen of the United States, and a resident of New York, in the county and State of New York, have invented certain new and useful Improvements in Punching-Machines, of which the following is a specification.

My invention has reference to improvements in punching-machines, and has for its purpose to provide a machine to facilitate the manufacture of keys for pianos and organs.

The piano and organ keys—the long or so-called "natural" as well as the short or so-called "sharp" keys—are sawed out of a blank of wood, so that all keys have a uniform thickness and length. Up to this time the longitudinal cuts to separate the keys longitudinally from each other were made by means of a band or scroll saw, and the small cuts to separate the short or sharp keys from the long keys were made by hand with a chisel. The latter manipulation is very troublesome and requires much time, which disadvantage is done away with by my improved punching-machine, which is illustrated in the accompanying drawings, in which—

Figure 1 is a side, and Fig. 2 a front, elevation of the machine. Fig. 3 represents a front view of the chisel-holding carriage, and Fig. 4 a side view of the same. Fig. 5 is a section on line 5 5 of Fig. 3. Fig. 6 shows a blank for the piano-keys, and Fig. 7 is a section on line 7 7 of Fig. 6.

Similar letters of reference indicate corresponding parts.

A in the drawings represents the frame of my machine, in the standards of which a shaft *a* is journaled, which receives rotary motion in the usual manner by belt and pulleys from any suitable power-generator. The shaft *a* has a cog-wheel *a'*, that meshes with two cog-wheels *a²* *a²*, journaled in one of the standards of the machine above and below, respectively, the cog-wheel *a'*. Each of the cog-wheels *a²* engages a cog-wheel *b'*, which cog-wheels *b'* are keyed on shafts *b*, also journaled in the standards and having on their ends projecting through the said standards a crank-arm *b²*, so that as soon as rotation is imparted to the main shaft *a* four crank-arms *b²* are simultaneously put in rotary motion.

The standards of the machine are recessed,

as clearly shown in Fig. 2, and the portions of the standards above and below the recesses have horizontal guide-grooves, in which 55 carriages *C* slide, as shown in Figs. 3 and 4. To these carriages up and downward motion is imparted by connecting-rods *c*, which are pivoted to the said carriages with one end and with the other end attached to the crank-arms 60 *b²*. The said crank-arms are slotted, as shown in Fig. 3, and the connecting-rods *c* are provided with pins *c'*, which project into the slits of the crank-arms and follow, when the shafts *b* are rotated, the rotating motion of the 65 crank-arms, and consequently move the carriages in their guide-grooves up and down.

The carriages are provided with set-screws *d*, which are screwed into the front portions of the same and serve to hold the chisels or 70 knives *D*. The latter have, for this purpose, slits *d'* through which the set-screws *d* pass, and when screwed down into the bodies of the carriages press upon the chisels or knives and hold them firmly in position, as shown in 75 Figs. 4 and 5. It is evident that by means of the said set-screws *d* the chisels can be adjusted on their respective carriages to any desired length, so that when they are moved up or down cuts of any desired depths into 80 wood or other blanks can be produced.

In the machine shown in the drawings the chisels on the carriages are so located that those on the upper carriages are right opposite those on the lower carriages, but the 85 chisels may be arranged otherwise according to the cuts required.

Instead of five chisels on each carriage, as shown in the drawings, less or more chisels may be attached to and operated by the carriages. The latter are furthermore provided with horizontal brackets *e*, through which vertical screws *e'* pass, which can be so set that they abut against the bases of the chisels and serve as supports for the same, so that 90 they are more reliably held on the set-screws *d* and cannot be brought out of their positions by the force of the strokes exerted by the same on the material to be punched. Laterally to the standards tables *E* are attached 95 in any required manner to support the material to be punched.

My improved punching-machine works in the following manner: Wood boards or blanks

F, on which the keys to be punched and sawed out are marked and divided into octaves by means of marking-holes *f*, (the space between two holes making one octave,) are placed on the tables E and pushed into the recesses in the standards of the machine until the pins *g* in the recesses are located in the said holes *f*. Rotary motion is then imparted to the main shaft *a* and like motion transmitted from the cog-wheel *a'* of the same to the cog-wheels *a²* *a³*, and from these by the cog-wheels *b' b'* to the shafts *b b* bearing the crank-arms *b² b²*, as explained before, it being understood that when the blanks F are in the required positions in the said recesses the shafts *b* are in such positions that the crank-arms on the lower shaft point downward and the crank-arms on the upper shaft point upward. By the rotary motion imparted to the said shafts *b* the crank-arms are swung up and down respectively, and the connecting rods, swiveled to the same, simultaneously moved in the same direction, whereby the carriages, which are pivoted to the connecting-rods, are shifted in the guide-grooves respectively up and down and the chisels on the carriages pierced into the blanks, thus producing the cuts *h*, Figs. 6 and 7, into the same. The vertical supporting-screws *e*, which abut against the lower ends of the chisels, prevent the latter from being removed out of their positions when the strokes are exerted upon the blanks, so that always even cuts are obtained. When the shafts *b*, with their crank-arms, are rotated further the carriages are moved in an opposite direction and the chisels withdrawn from the blanks. In the meantime the blanks are released from the pins *g* and moved on until the pins reach the next holes *f*, whereafter the described operation is repeated. When the whole blank is punched in the described manner the longitudinal cuts are made into the same by means

of a band or scroll saw and the short or so-called "sharp" keys broken off from the long 45 or so-called "natural" keys.

The chisels or knives may be arranged in any other way, as said before, so that my machine may also serve other purposes and can be used for punching any other articles out 50 of wood as well as of metal.

Having thus described my invention, I claim as new and desire to secure by Letters Patent—

1. The combination of a rotary main shaft 55 bearing a cog-wheel, with secondary rotary shafts having crank-arms and being in rotary connection, by means of cog-wheels, with the main shaft, carriages having adjustable chisels and sliding in guide-grooves in the frame 60 of the machine, the carriages being connected with the said crank-arms by means of connecting-rods, so that by the rotation of the shafts the carriages are simultaneously moved to and from each other, substantially as set 65 forth.

2. In a punching-machine, the combination of the frame having inwardly-extending recesses, with a rotary main shaft, two secondary rotary shafts, one above and the other 70 one below the said recesses, the secondary shafts being connected with the main shaft by means of cog-wheels, crank-arms attached to the secondary shafts, connecting-rods attached to the crank-arms, and carriages pivoted to the connecting-rods and sliding in the frame toward and from each other, the carriages bearing adjustable chisels and vertical screws which latter abut against the said chisels and support the same, substantially 75 as set forth.

FRIEDRICH PHILIPP.
